UNITED STATES PATENT OFFICE.

WILLIAM F. SPIETH, OF CLEVELAND, OHIO.

COMBINATION COOKING-RANGE.

1,231,087.

Specification of Letters Patent. Patented June 26, 1917.

Application filed April 13, 1916. Serial No. 90,882.

To all whom it may concern:

Be it known that I, WILLIAM F. SPIETH, a citizen of the United States, residing at Cleveland, in the county of Cuyahoga and 5 State of Ohio, have invented a certain new and useful Improvement in Combination Cooking-Ranges, of which the following is a full, clear, and exact description.

The object of this invention is to provide 10 a cheap and efficient cooking range which can burn either coal or gas as fuel.

The invention consists in the construction and combination of parts shown in the drawing and hereinafter described and definitely pointed out in the appended claims.

In the drawing, Figure 1 is a perspective view of a cooking range which embodies the invention,—the oven door being omitted. Fig. 2 is a top plan view, with the rear part 20 sectioned in the plane of line 2—2 on Fig. 3. Fig. 3 is a sectional front view in the plane of line 3—3 on Fig. 2. Fig. 4 is a sectional end view in the plane of line 4—4 on Fig. 2. Fig. 5 is an enlarged vertical section 25 through the left burner box and adjacent part of the end of the stove, and Fig. 6 is a left end view of the front part of the left burner box, when the outer plate thereof has been removed.

30 The stove which is shown in the drawing, and in which the invention is embodied, is of familiar construction in so far as concerns those characteristics of construction which adapt it to burn coal and utilize the 35 resultant heat for cooking purposes. It contains in one end (the left end) a coal burning fire pot 10. It likewise contains an oven 12 which is spaced away from the top 14, the right end 16, and the bottom 17 of 40 the stove, so as to form within the stove and around the oven, the top oven flue 20, the end oven flue 21, and the bottom oven flue 22,—which flues are serially in open communication with one another. The left end of 45 the oven serves as the inner wall of the fire pot. This wall should not extend much if any above the top of the oven; wherefore the fire pot is in open communication with the top oven flue. On the rear side of the stove 50 is a smoke box 23. The bottom oven flue 22 communicates with this smoke box through a suitable opening 24 in the rear wall of the stove. The top oven flue 20 also communicates with the smoke box through an opening 25 in the rear wall of the stove; and a

damper 26 is provided for closing this opening when desired.

In order that the above described coal burning cooking range may be adapted to burn gas, and to perform all of the functions which it can perform when coal is burned, but in a more economical and satisfactory manner, two burner boxes 30 and 40 are respectively secured to opposite ends of the stove just below the top thereof; and these burner boxes communicate with the interior of the stove through long narrow horizontal slots 18^a, 16^a, in the ends of the stove,—each of which slots is provided with a damper. Each of these burner boxes is 70 preferably open at its bottom; and it contains a pipe burner, that is, a pipe having rows of jet openings; and each burner is of course, associated with means for supplying gas thereto as desired. 75

The specific construction shown in the drawing for producing the combination stove, above referred to in general terms, is as follows: Each burner box comprises an inner wall 31, two end walls 32, a top 33, 80 and a removable outer wall 34; but it has no bottom. A slot 35 is formed in the inner wall 31, and this is surrounded by a marginal flange 36 which is passed through and fits the adjacent slot 18^a, 16^a, above referred 85 to, formed in that end wall of the stove to which the burner box is secured by suitable means. The inner surface of the lower wall of this flanged slot 35 is beveled or curved as shown at 37. Within the box a damper 50 90 is pivoted, said damper being adapted to cover or uncover the slot 35 as required.

A horizontal pipe burner 52 is arranged in the burner box just below the slot 35; and in this pipe burner are two rows of jet 95 holes 53 disposed at such angle that they will discharge directly into the adjacent slot 35. To support the pipe burner two ring brackets 38 are formed on the inside face of the wall 31. The pipe burner 52 goes 100 through these ring brackets, and is fixed therein with the jet holes at the proper inclination, by set screws 39.

The burner in the burner box that is fixed to the left end of the stove contains an internal cross partition 54 which in effect makes two burners out of this pipe. The front burner is supplied with gas through a valve controlled gas pipe 55; and the rear burner is independently supplied with gas 110

from the valve controlled gas pipe 56. The burner in the burner box at the right end of the stove is independently supplied with gas through the valve controlled gas pipe 57.

5 It will be readily understood that if one wishes to burn coal in this stove he may do so by keeping both of the dampers 50 closed. If, however, he wishes to use gas as fuel, and wishes to be able to heat cooking utensils 10 placed anywhere on the top of the stove, and wishes at the same time to bake in the oven, he will close the damper 26, will close the damper in the right burner box, and will open the damper in the left burner box, and 15 will light both of the burners in said left burner box. The result will be that a wide sheet of flame will sweep out of the burner box through the flanged slot thereof into the stove, and will flow beneath the entire 20 top of the stove through the open flue 20, then down in the oven flue 21, and under the oven in flue 22, and into the smoke box through the opening 24.

If one wishes merely to bake and not to 25 cook on the top of the stove, he will close the damper in the left burner box and open the damper in the right burner box and light the burner therein. A sheet of flame will pass out of the burner box through the flanged slot therein into the stove, and thence down the oven flue 21 into the oven flue 22 and into the smoke box through the opening 24. If he wishes to cook at all points 30 on the top of the stove, but does not wish to heat the oven, he will open the damper 26 and the dampers in both burner boxes, and light the burners in said burner boxes. If he desires to heat only a part of the stove top for the purpose of cooking thereon, he 35 may accomplish this in various ways. To heat the two left rear stove covers he will light the rear burner in the left oven box, will open the damper of said burner box, and will open the damper 26, and close the 40 damper in the right burner box. To heat the two right stove holes and the two middle stove holes one may light the burner in the right hand burner box and open the damper thereof and close the damper of the left 45 hand burner box, leaving the damper 26 open.

From the foregoing it is seen that one gets with the construction shown a very great and very advantageous control of the stove, 50 and is able with gaseous fuel to cause the stove to perform any or all of its ordinary functions, and to economically use fuel to produce these results. The construction not only enables the saving of fuel and the satisfactory employment of the stove, but it is 55 of considerable advantage in the summer time when one only wants to heat the stove to do some particular bit of cooking and wants to avoid having the stove heated to a 60 degree as will heat the kitchen.

Having described my invention, I claim:

1. A cooking stove having in one end a coal burning fire pot, and containing an oven which is spaced away from the top, bottom and opposite end of the stove to form 70 communicating top, end and bottom oven flues, said oven being separated from the fire pot by a common partition wall which does not extend up to the top of the stove whereby the fire pot is in open communication with 75 the top oven flue, a smoke box which is in communication with the bottom oven flue and is also in communication with the top oven flue, a damper controlling the last named communication, a bottomless burner 80 box secured to the outer face of that end of the stove which is adjacent said fire pot, there being a slot through said end of the stove whereby to establish communication between the burner box and fire pot, a 85 damper for controlling said slot, a perforated burner pipe arranged horizontally in said burner box below said slot, and means to supply gas to said burner pipe.

2. A cooking stove having in one end a 90 coal burning fire pot, and containing an oven which is spaced away from the top, bottom and opposite end of the stove to form communicating top, end and bottom oven flues, said oven being separated from the fire pot 95 by a common partition wall which does not extend up to the top of the stove whereby the fire pot is in open communication with the top oven flue, a smoke box which is in communication with the bottom oven flue 100 and is also in communication with the top oven flue, a damper controlling the last named communication, a bottomless burner box secured to the outer face of that end of the stove which is adjacent said fire pot, 105 there being a slot through said end of the stove whereby to establish communication between the burner box and fire pot, a damper for controlling said slot, two aligned perforated burner pipes arranged horizontally 110 in said burner box below said slot, and means to independently supply gas to said two burner pipes.

3. A cooking stove having in one end a 115 coal burning fire pot, and containing an oven which is spaced away from the top, bottom and opposite end of the stove to form communicating top, end and bottom oven flues, said oven being separated from the fire pot by a common partition wall which does not 120 extend up to the top of the stove whereby the fire pot is in open communication with the top oven flue, a smoke box which is in communication with the bottom oven flue and is also in communication with the top oven flue, a damper controlling the last-named communication, there being a long 125 horizontal slot in each end of the stove near the top thereof, a burner box secured to the outer face of each end of the stove 130

over the slot therein, a damper for each of said slots, a perforated burner pipe arranged horizontally in each of said burner boxes below the associated slot, and means to independently supply gas to said burner pipes.

4. A cooking stove having in one end a coal burning fire pot, and containing an oven which is spaced away from the top, bottom and opposite end of the stove to form communicating oven flues, said oven being separated from the fire pot by a partition wall which does not extend to the top of the stove whereby the fire pot is in open communication with the top oven flue, a smoke box which is in communication with the top oven flue and bottom oven flue, a damper controlling the first named communication, the end of the stove adjacent the fire pot having a long horizontal slot through it just below the top of the stove, a burner box which is secured to said slotted end of the stove over the slot therein, said burner box being open at its bottom and having in that side which is in contact with the stove end a horizontal slot which is provided with a marginal flange that passes through and fits the slot in the stove end, a damper within and supported by said burner box for covering and uncovering said flanged slot, a perforated pipe burner supported by the burner box and located therein just below said flanged slot,—the perforations in said pipe being directed to discharge directly into said slot, and valve controlled means to supply gas to said burner.

5. A cooking stove having in one end a coal burning fire pot, and containing an oven which is spaced away from the top, bottom and opposite end of the stove to form communicating oven flues,—said oven being separated from the fire pot by a partition wall which does not extend to the top of the stove whereby the fire pot is in open communication with the top oven flue, a smoke box which is in communication with the top oven flue and bottom oven flue, a damper controlling the first named communication,—the end of the stove adjacent the fire pot having a long horizontal slot through it just below the top of the stove, a burner box which is secured to said slotted end of the stove over the slot therein said burner box being open at its bottom and having in that side which is in contact with the stove end a horizontal slot which is provided with a marginal flange that passes through and fits the slot in the stove end, a damper within and supported by said burner

box for covering and uncovering said flanged slot, two aligned perforated pipe burners supported by the burner box and located therein just below the said flanged slot, the perforations in said burners being directed to discharge into said slot, and independent valve controlled gas supply devices for said two burners.

6. A cooking stove having a horizontal flue just below the top of the range and having in one end a horizontal slot which extends substantially from front to rear of said stove and is in substantially the same horizontal plane as said flue, a burner box rigidly fixed externally to said end of the stove over the slot therein; which burner box is open at its bottom and has through its inner wall a horizontal slot which corresponds and registers with the slot in the end of the stove, a marginal flange formed integral with the slotted wall of said burner box around the slot therein,—which flange passes through and fits the slot in the end of the flange, a pipe burner located in said box slightly below said slot which burner pipe has a row of perforations directed at an angle toward said slot, and means to supply gas to said burner pipe.

7. A cooking stove having a horizontal flue just below the top of the range, having in one end a horizontal slot which extends substantially from the front to the rear of said stove and is in substantially the same horizontal plane as said flue, a burner box rigidly fixed externally to the end of said stove over the slot therein which burner box is open at its bottom and has in its inner side a slot, a marginal flange formed integrally with the slotted wall of said burner box around the said slot,—which flange projects through and fits the slot in the end of the range, a pair of ring brackets within said burner box, a pipe burner rotatably fitted in said ring brackets and having a horizontal row of perforations, means for clamping said pipe burner to one of said ring brackets to prevent the rotation of the pipe burner when the same is located in position such that the perforations therein will discharge at the proper angle toward the said slot, and means to supply gas to said pipe burner.

In testimony whereof, I hereunto affix my signature in the presence of two witnesses.

WILLIAM F. SPIETH.
